Attorney.

UNITED STATES PATENT OFFICE.

CLARENCE S. STEWARD, OF CHATTANOOGA, TENNESSEE.

GAS-BURNER.

SPECIFICATION forming part of Letters Patent No. 636,080, dated October 31, 1899.

Application filed March 22, 1898. Serial No. 674,805. (No model.)

To all whom it may concern:

Be it known that I, CLARENCE S. STEWARD, of Chattanooga, in the county of Hamilton, State of Tennessee, have invented certain new and useful Improvements in Gas-Burners, of which the following is a complete specification, reference being had to the accompanying drawings.

The object of my invention is to produce improvements in burners for facilitating the use of gases that are rich in carbon—such, for example, as acetylene gas—whereby air may be supplied to and commingled with the gas prior to its ignition in such proportion as to promote perfect combustion.

In the accompanying drawings, Figure I is a perspective view of one form of my burner complete. Fig. II is a perspective view of a slightly-modified form of burner. Fig. III is a perspective view of a multiple burner constructed upon the same principle as the burner shown in Figs. I and II. Fig. IV is a central vertical section of the subject-matter of Fig. I. Fig. V is a central vertical section of the subject-matter of Fig. II. Fig. VI is a central vertical section of the subject-matter of Fig. III.

Referring to the figures on the drawings, I indicates the head of my burner, which may 30 be made of a piece of steatite, talc, clay, metal, or any suitable material, preferably steatite.

In the single form of burner shown in Figs. I and II the shape of the burner is preferably bulbous; but that may be modified in any respect, as required or preferred.

The head is provided with a collar 2, that affords means of uniting the head to a source of gas-supply—as, for example, a pillar 3. 40 The collar may be formed integrally with the head, as shown in Figs. I and II, or it may be formed separately therefrom and united to the head, as by a tapered and cemented joint, screw-threads, or other suitable means.

Referring particularly to Figs. I and II, I provide in the top of the head a recess 4, preferably a transverse recess cutting entirely across the head. The shape of the recess, however, may be modified, that illustrated 50 being merely a simple form and one which may be conveniently made. The recess 4 is preferably V-shaped, being defined by walls

5 and 6, inclined toward each other in order to accommodate opposite apertures 7 and 8, whose inclination is such as to cause columns 55 of commingled air and gas issuing therefrom to impinge against each other at a suitable height above the recess 4. The apertures 7 and 8 intercept transverse air-supply apertures 9 and 10, extending transversely through 60 the wall of the head. In like manner they may also intercept apertures 11 and 12, formed at right angles to the apertures 9 and 10, as shown in Figs. II and V, for example. Opposite the apertures 7 and 8 I provide minute gas-ducts 13, which, communicating with the bore 14 of the collar 2, afford means of gas-supply to the discharge-orifices 7 and 8.

The mode of communication with the bore 14 may be varied. It may, for example, be 70 made through a conoidal cavity 15, formed by a suitable instrument in the head of the burner, or it may be made by obliquely-disposed ramifications 16, originally extending through the outer wall of the head 1 to the 75 interior of the bore 14, but afterward cemented shut, as clearly shown in Fig. II of the drawings. The two forms of communication between the ducts 13 and the bore of the collar are presented merely by way of illustration and as indicative of the fact that a variety of modes of communication may be employed.

In Figs. III and VI of the drawings I illustrate a multiple burner constructed upon the 85 principle of the burner above described. In these figures, 16 indicates an oblong head provided with a collar 17. The head is provided with a gas-cavity 18, communicating with the bore of the collar 17. The cavity 18 may be 90 formed by a suitable instrument from one end of the head and may afterward be closed by cement or otherwise, as illustrated in Fig. III of the drawings. 19 indicates a trough or groove in the upper face of the head, upon 95 opposite sides of which are formed air-supply apertures 20, consisting of holes drilled longitudinally through the head. Other air-supply apertures may be provided than those illustrated if the number of flames carried by 100 the head require greater supply of air than can be afforded by the air-supply apertures illustrated. At suitable intervals in the groove 19 I provide oppositely-discharging ori-

fices 21. These orifices intercept the air-supply apertures 20 and communicate through them with gas-ducts 22, that afford communication with the interior of the gas-cavity 18.

In the drawings two oppositely-discharging orifices 21 are illustrated; but a greater number may be supplied if more than two flames to each head are required.

10. In operation gas from a suitable source is supplied under pressure to the bore 14 of the collar of the burner. Thence passing to the gas-ducts it issues in a fine stream to the interior of the gas-supply aperture, where commingling with air it passes outwardly through the apertures 7 and 8 of the single burner or through the apertures 21 of the multiple burner. Issuing from the apertures above described the columns of commingled gas and 20 air are ignited and, impinging against one another, form a flat and well-dispersed brilliant flame.

It may be noted in this connection that the orifices for the discharge of commingled gas and air are formed in the wall of the burner-head itself without employment of tips or projecting members of any sort whatsoever.

What I claim is—

30. 1. The combination with a substantially cylindrical burner-head provided across the top with a transverse V-shaped recess and

with a bore, of gas-ducts, communicating with the bore and discharging oppositely through the inclined walls of the recess in the burner-head, substantially as set forth. 35

2. The combination with a substantially cylindrical burner-head provided across the top with a transverse V-shaped recess, a bore, and gas-ducts communicating with the bore, 40 of oppositely-discharging orifices in the inclined walls of the recess opposite the respective ducts, substantially as set forth.

3. A multiple burner, consisting of a head provided with a plurality of pairs of oppositely-discharging orifices, an internal gas-cavity, gas-ducts communicating with the orifices, respectively, and means of air-supply to the respective orifices, substantially as 45 set forth. 50

4. A multiple burner, consisting of a head provided with a cavity, a plurality of pairs of oppositely-discharging orifices, and gas-ducts communicating between said orifices and the cavity, and air-supply apertures, each of 55 which communicates with a plurality of orifices, substantially as set forth. 55

In testimony of all of which I have hereunto subscribed my name.

CLARENCE S. STEWARD.
